United States Patent Office

Des. 177,729
Patented May 22, 1956

177,729

ELECTRIC RECEPTACLE

John A. Herrmann, Grosse Pointe Farms, and John B. Cataldo, Birmingham, Mich., assignor to BullDog Electric Products Co., Detroit, Mich., a corporation of West Virginia

Application March 3, 1954, Serial No. 29,304

Term of patent 14 years

(Cl. D26—1)

Fig. 1 is a top plan view of an electrical receptacle showing our new design.

Fig. 2 is a front elevational view of the receptacle.

Fig. 3 is an end view of the receptacle.

Fig. 4 is an end view of the receptacle.

Fig. 5 is a rear elevational view of the receptacle.

We claim:

The ornamental design for an electric receptacle, substantially as shown.
